COMBINED INK-MARKING AND PERFORATING MACHINE

Arthur W. Altvater, University City, Mo.

Application July 7, 1937, Serial No. 152,341

15 Claims. (Cl. 101—316)

The present invention relates to shoe machines and more particularly to machines for performing combined ink-marking and perforating operations.

5 Cut-out machines, such as the well-known "Western," are used extensively in the shoe industry to perform perforating and cut-out operations in shoe uppers and various parts thereof. Ink-marking attachments have been used 10 also in connection with these well-known type of machines. Heretofore, it has been necessary to remove these attachments in order to restore the "Western" machine to its regular perforating operation. In these attachments, the operative was 15 obliged to actuate, through use of her hands, the mechanism for bringing the inking means and the marking edges of the die into engagement in order to ink them. Furthermore, in these attachments, it was considered necessary to pivot 20 the ink pad about an axis adjacent the front of the machine in order to expose it for a re-inking operation. Moreover, in these attachments the marking edges were not conveniently accessible to the operative so that they might be 25 cleaned while the die remained in the machine.

The principal objects of the present invention are to produce a combined ink-marking and perforating machine, which may be used also for marking, perforating or cutting-out merely by 30 substituting the proper type of die for the combined ink-marking and perforating die, in which the die may be elevated to engage its marking edge with the inking means by the operative without the use of her hands, in which the ink 35 pad may be swung about an axis located remote from the operative instead of adjacent thereto, and in which the marking edges may be exposed conveniently to the operative for cleaning purposes while the die remains in the machine.

40 To the accomplishment of these objects, and such others as may appear hereinafter, the various features of the present invention reside in certain devices, combinations and arrangements of parts hereinafter described and then set forth 45 broadly and in detail in the appended claims which possess advantages readily apparent to those skilled in the art.

The various features of the present invention will be readily understood from an inspection 50 of the accompanying drawings illustrating the best form of the invention at present known to the inventor, in which,

Figure 1 is a view in right side elevation, partly in section, of the "Western" cut-out machine;

55 Fig. 2 is an enlarged detail view in plan show-

ing the mechanism for converting the "Western" into a combined ink-marking and perforating machine;

Fig. 3 is an enlarged detail view of the parts illustrated in Fig. 2;

Fig. 4 is an enlarged detail view in front elevation of the parts illustrated in Figs. 2 and 3;

Fig. 5 is a detail view in sectional elevation on the line 5—5, Fig. 2, illustrating the sponge rubber ink pad, the supporting guard plate therefor, 10 the skeleton frame to which the guard plate is connected detachably, one of the die lift rails and the treadle-connected mechanism for lifting them, and

Fig. 6 is a detail view in front sectional elevation on the line 6—6, Fig. 5.

As shown in Fig. 1, the "Western" cut-out machine comprises a bed 7, a pressing member 8, a face plate 9 thereon, and a paper-cutting bed 10 for the face plate, generally in accordance with 20 standard cut-out machine construction. The invention disclosed in the application filed jointly by Arthur W. Altvater and Franz Wunder, April 16, 1937, Serial No. 137,256, comprises an attachment for the "Western" cut-out machine which 25 converts it into a combined ink-marking and perforating machine, which attachment is removed to restore the "Western" to its normal perforating or cut-out function.

The illustrated embodiment of the present invention converts also the "Western" into a combined ink-marking and perforating machine but in a manner which permits the "Western" to perform a combined ink-marking and perforating operation, a marking operation, or a perforating 35 or cut-out operation merely by the insertion of the proper die therein.

Referring more particularly to Figs. 2 and 3, the upper surface of the bed 7 supports a pair of rails 11 and 12 which are connected as is the 40 usual manner in the "Western" machine for sliding movement across the supporting face of the bed towards and from each other. The rails 11 and 12 are provided, respectively, with forward extensions 13 and 14, the bottom faces of which, 45 (Fig. 4), support, respectively, elongated brackets 15 and 16. The inside faces of the brackets 15 and 16 support, respectively, die lift rails 17 and 18, (Fig. 2). To this end, each bracket carries a pair of horizontal screws 19, (Fig. 5), the 50 shanks of which pass loosely, respectively, through slots 20 which are inclined forwardly and upwardly, a head on the screw 19 serving to hold the die lift rail on its supporting bracket while permitting the die lift rail to move rela- 55

tively thereto in a manner and for a purpose to be described.

The rails 11 and 12 and the extensions thereof, embrace the sides of the combined ink-marking and perforating die 21, (Figs. 2 and 3), and guide it for sliding movement from the position of clearance to and from the position of pressure. The die 21 is supported directly by the bed 7 while it is in the position of pressure, in which position the machine performs the combined ink-marking and perforating operation. The die 21 is supported both by the elongated brackets 15 and 16 and the die lift rails 17 and 18 while it is in the position of clearance, in which position the operative removes the inked and marked work and locates another work piece on the die for the next combined ink-marking and perforating operation.

The die 21 comprises a series of perforating tubes 22 and a series of markers 23, both series being constructed, associated and mounted in the usual manner. The perforating tubes 22, (Fig. 3), are mounted in a tube holder plate 24 which rests upon a tube rest plate 25. The plates 24 and 25 are mounted upon a bottom plate 26 to the front face of which a handle 27 is connected. The handle 27 extends forwardly in position to be grasped by the operative to facilitate the sliding of the die from, and to, a position of clearance to, and from, a position of pressure.

As usual in the manufacture of stitch-marking dies, so called, the markers 23 are formed by routing them out of a solid brass blank so that the marking edges rise vertically from a flat plate 28 integral therewith. The plate 25 is perforated as shown in Fig. 2 to permit the passage of the tubes 22 therethrough. As usual in this type of die, the plate 28 is connected loosely to the tube holder and tube rest plates 24 and 25, there being the usual series of springs (not shown) interposed between the bottom of the plate 28 and the top of the tube holder plate 24.

The work during the ink-marking and perforating operation is supported upon a stripper plate 29 having the usual opening 30 therein across which the work is drum-headed during the combined ink-marking and perforating operation. The work-supporting surface of the stripper plate 29 is provided also with the usual gauging pins 31, of the bumper type and with the usual work clamps 32, of the leaf spring type.

Experience has demonstrated that the mark made by the markers 23 on the work should be sharply defined to provide the operative in the subsequent operation with a legible guide line. At the same time the sharply-defined line should be delicate to insure its registry with the overlapped overlay, other assembled part, or the fancy stitches. If excess ink is allowed to dry on the marking edges they become thickened thereby with the result that the work is marked with a wide, ragged line which causes irregularities in the subsequent operation. As the overlapped part, an applique, an assembled upper blank, a gimp, or a fancy stitch cannot hide completely the wide, ragged line, the exposed portions thereof must be removed before the shoes can be sold. The ink removal operation takes place when the shoes are finished and therefore considerable care and labor must be expended in removing the exposed ink mark to avoid spoilage.

Heretofore considerable difficulty has been experienced in maintaining the marking edges in a combined ink-marking and perforating die of the type disclosed herein free from accumulations of

dried ink. Heretofore it has been found impracticable to clean such marking edges while the die remained in the machine.

In order to facilitate the cleaning of the marking edges 23 while the die 21 remains in the machine, the stripper plate 29 is pivoted about a horizontal axis located at the rear of the die so that the stripper plate 29 when located in the position of clearance may be swung upwardly in a direction extending away from the operative to expose the marking edges 23 thereto.

To this end the bottom of the stripper plate 29 at the rear end corners thereof are provided with blocks 33 and 34, (Fig. 2), which are received in and pivoted to the arms of yokes formed, respectively, in rails 35 and 36. These rails are carried upon the upper ends of studs 37 which pass loosely through tube holder and tube rest plates, there being a head 38 on each stud, which works in an opening 39 formed in the tube rest and bottom plates and engages the bottom of the tube holder plate.

The stripper plate 29 is held normally in the position of Fig. 3 by a plurality of coiled springs 40, the bottom ends of which are seated in the tube holder plate and the upper ends of which are engaged with the bottoms of the rails 35 and 36.

With this construction, the stripper plate 29 may be swung upwardly from the full line position of Fig. 3 to the construction line position thereof, in a direction rearwardly, that is, in a direction away from the operative, to expose the markers thereto and thus facilitate their cleaning when required. The stripper plate 29 may be clamped in the position of Fig. 3 by a pair of pins 41, only one of which is shown in Fig. 3. Each pin 41 depends from the bottom of the stripper plate 29 in position to pass loosely through an opening 42 formed in the stripper plate supporting rail. The bottom of the pin 41 is tapered and is arranged to be inserted into one of the forward coiled springs 40, the upper coils of which grip the tapered portion of the pin and lock securely the stripper plate in operating position.

In order to ink the marking edges 23 each time the die is moved into the position of clearance from the position of pressure, inking means is provided which is first inserted between the marking edges 23 and the bottom of the stripper plate 29 and then the marking edges are moved vertically to cause them to engage the inking means. With this construction, all danger of depositing ink upon the work-supporting surface of the stripper plate 29 is obviated.

The inking means comprises a sponge rubber ink pad 43, (Figs. 5 and 6), which is cemented or otherwise secured to the bottom of a flat guard plate 44. The guard plate 44 is carried by a skeleton frame. As shown more particularly in Fig. 2, the frame is provided with a rear end 45 and side portions 46 and 47, the inside faces of which are provided with grooves 48 which receive the side edges of the guard plate 44. The rear edge of the guard plate 44 is bent downward, which bent edge engages the rear end 45 of the frame when the pad 43 is positioned therein. The sides of the frame are braced by a cross piece 480, Fig. 5.

As illustrated in Fig. 2 the side edges 46 and 47 of the skeleton frame extend forwardly to the ends of the rails 13 and 14, are then bent laterally away from each other and then forwardly parallel to each other. Near the laterally bent portions, the side edges 46 and 47 are pivoted on studs 49 and 50, respectively, which project laterally from the free forward ends of supporting arms 51 and 52. 75

The rear ends of the arms 51 and 52 are bent upwardly and are pivoted on studs 53 and 54 projecting laterally from brackets 55 and 56 rising, respectively, from the rails 13 and 14.

5 The rearward extending portions of the skeleton frame arms 46 and 47 are held normally, (Fig. 2), respectively, against the bottoms of stops 57 and 58 carried by the arms 51 and 52, by coiled springs 570 and 580, (Fig. 4), one end of each of 10 which is connected to the skeleton frame and the other end of each of which is connected to the pivoted arm 51 or 52.

Thus the skeleton frame, and the ink pad supported therefrom, is pivoted about two independent axes. If the stripper plate 29 should be so large as to extend over the guard plate 44 during the combined ink-marking and perforating operation the stripper plate harmlessly causes the guard plate to swing downwardly about the axis of the 20 studs 49 and 50 against the tension of the springs 570 and 580. The skeleton frame and the ink pad supported therefrom may be swung upwardly in a direction away from the operative about the axis of the studs 53 and 54 to expose the sponge 25 ink pad to facilitate its inking and its withdrawal from inking position so that the "Western" machine may be used for perforating, cutting out or marking in the usual manner, that is, without inking.

30 The arms 51 and 52 are locked from movement upwardly when the pivoted ink pad is located for the inking operation by latches 59 and 60 pivoted, respectively, on the elongated brackets 15 and 16. Each latch is provided with a downwardly bent 35 end 61 and an intermediate notch 62, (Fig. 2), the notch embracing a pin 62 depending from the arms 51 and 52, respectively.

In the illustrated embodiment of the invention, when the combined ink-marking and perforating 40 die 21 is moved from a position of pressure to a position of clearance, the stripper plate 29 rides over the upper surface of the guard plate 44, thus inserting the ink pad 43 between the marking edges 23 and the stripper plate. The stripper 45 plate studs and supporting springs are mounted to clear the lateral sides of the ink pad and its supporting means when the die is moved from the position of pressure into the position of clearance.

Referring now to Figs. 4 and 5, the forward end 50 of each die-lifting rail 17 and 18 is provided with a stop 63. Heretofore when the operative moved the die from the position of pressure into the position of clearance, she was obliged to engage the front face of the die with the stops and then pull 55 hard on the die in order to move the die-lifting rails forwardly and upwardly to carry the die off the brackets 15 and 16 and the marking edges 23 into engagement with the ink pad 43.

In order to free the operative's hands to the 60 sole duty of removing one piece of work and of substituting another piece of work therefor when the die is in a position of clearance, in the illustrated embodiment of the invention, the die-lifting rails are actuated from a treadle to cause 65 them to lift the marking edges 23 into engagement with the ink pad.

To this end, the die-lift rails 17 and 18 are provided, respectively, with depending rear ends 64 and 65, (Fig. 4). Journalled in the elongated 70 brackets 15 and 16 is a rock shaft 66 provided with arms 67 and 68. The arms 67 and 68 are provided with horizontal pins 69 and 70, respectively, engaged with the ends 64 and 65 of the die-lift rails 17 and 18, respectively. The rock shaft 66 is 75 provided with a third arm 71, (Figs. 4 and 5), to

which the upper end of a treadle rod 72 is hooked, the treadle rod being suitably urged upwardly by a spring 73, (Fig. 1), to restore the parts operatively connected to the treadle to their normal position upon its release by the operative. The 5 arm 71 is provided with a stop screw 73, (Figs. 1, 4 and 5), the point of which engages the front face of the bed 7 in order that the normal relationship between the pins 69 and 70 and the portions 64 and 65 of the rails 17 and 18, respectively, 10 may be adjustably controlled.

In order to control adjustably the force with 15 which the marking edge of the die 21 engages the ink pad 43, the front face of the bracket 16 carries a screw 74, (Figs. 1, 3 and 4), the point of 20 which is arranged to engage the front end of the die-lift rail 18 and limit the forward and upward movement of both of the die-lift rails under the influence of the treadle-controlled die-lifting mechanism.

Nothing herein explained is to be interpreted as 25 limiting the various features of the present invention in the scope of its application to use in connection with the particular machine or the particular mode of operation or any combination thereof selected for purposes of illustration and explanation. While the particulars of construction herein set forth are well suited to one mechanical form of the invention and to the uses to 30 which it is put, it is not limited as to these uses, nor to these details of construction, nor to the 35 conjoint use of all its features, nor is it to be understood that these particulars are essential since they may be modified within the skill of the artisan without departing from the true scope of the actual invention, characterizing features of which are set forth in the following claims by the intentional use of generic terms and expressions inclusive of various modifications.

What is claimed as new is:

1. A combined ink-marking and perforating 40 machine having, in combination, a marking die provided with at least one marking edge, marking edge inking means, a support located at the position of clearance for supporting the die therein, and treadle-controlled means for moving the inking 45 means and the support relatively to engage the marking edge and the inking means.

2. A combined ink-marking and perforating 50 machine, having, in combination, a marking die provided with at least one marking edge, marking edge inking means, supports located at the position of clearance and pressure, respectively, for supporting the die therein, means for moving the die from one support to the other, and separate 55 means for moving the inking means and the position of clearance support relatively to engage the marking edge and the inking means.

3. A combined ink-marking and perforating 60 machine having, in combination, a marking die provided with at least one marking edge, marking edge inking means, supports located at the position of clearance and pressure, respectively, for supporting the die therein, means for moving the die from one support to the other, and treadle-controlled 65 means for moving the inking means and the position of clearance support relatively to engage the marking edge and the inking means.

4. A combined ink-marking and perforating 70 machine, having, in combination, a marking die provided with at least one marking edge, a stationary ink pad, a support located at the position of clearance for supporting the die therein, and treadle-controlled means for moving the support 75 to engage the marking edge and the inking means.

5. A combined ink-marking and perforating machine having, in combination, a stripper plate, a marking die provided with at least one marking edge spaced from the stripper plate, means 5 for inking the marking edge, and means, including treadle-controlled mechanism, for moving the inking means and the marking edge relatively in two directions substantially normal to each other to insert the inking means between the stripper 10 plate and the marking edge and to engage the marking edge and the inking means.
6. A combined ink-marking and perforating machine having, in combination, a stripper plate, a marking die provided with at least one marking edge spaced from the stripper plate, a stationary ink pad, means for moving the stripper plate and the marking edge in one direction to 15 insert the ink pad between the marking edge and the stripper plate, and treadle-controlled means 20 for moving the marking edge in another direction to cause it to engage the ink pad.
7. A marking machine having, in combination, a pair of marking die rails, each having a vertical bracket, a stop and a latch thereon, a support 25 pivoted on each bracket, a skeleton frame, having two sides, each side being pivoted to one of the supports, mounted between the rails, an ink pad supported from the frame, a spring interposed between each side and its support for maintaining 30 normally the sides engaged with the bottom of the stops, respectively, and means on the supports cooperating with the latches, respectively.
8. A combined ink-marking and perforating machine, having, in combination, a combined 35 ink-marking and perforating die, having upstanding marking and perforating edges and a stripper plate normally overlying them, means for moving the die from, and to, a position of clearance to, and from, a position of pressure, and means permitting 40 the stripper plate to be swung about a horizontal axis located adjacent its rear edge when the die is located in the position of clearance to expose the marking edges to the view of and access by the operative.
9. A marking machine having, in combination, 45 a marking die having at least one marking edge, a support for the die including at least one die lift rail, inking means for the marking edge, means for supporting the rail for movement upwardly and forwardly, means for moving the rail 50 upwardly and forwardly to engage the marking edge and the inking means including a rock shaft operatively connected to the rail, and treadle-controlled mechanism for rocking the rock shaft.
10. A marking machine having, in combination, 55 a marking die having at least one marking edge, a support for the die including at least one die lift rail, inking means for the marking edge, means for supporting the rail for movement upwardly and forwardly, means for moving the rail 60

upwardly and forwardly to engage the marking edge and the inking means including a rock shaft operatively connected to the rail and treadle-controlled mechanism for rocking the rock shaft, and a stop for limiting the movement of the rail. 5

11. A marking machine having, in combination, a marking die having at least one marking edge, a support for the die including at least one die lift rail, inking means for the marking edge, means for supporting the rail for movement upwardly and forwardly, and means for moving the rail upwardly and forwardly to engage the marking edge and the inking means including a rock shaft operatively connected to the rail and treadle-controlled mechanism for rocking the rock shaft and a stop for limiting the movement of the treadle-controlled mechanism. 10

12. A marking machine having, in combination, a marking die having at least one marking edge, a support for the die including at least one die lift rail, inking means for the marking edge, means for supporting the rail for movement upwardly and forwardly, and means for moving the rail upwardly and forwardly to engage the marking edge and the inking means including a rock shaft operatively connected to the rail and treadle-controlled mechanism for rocking the rock shaft and a stop for limiting the movement of the treadle-controlled mechanism. 15

13. In a marking machine, the combination with inking means, a support therefor, and a stripper plate normally having a path of movement which clears the support, of safety means permitting the support to yield in the accidental 35 event the stripper plate fails to clear the support.

14. In a marking machine, the combination with inking means and a support therefor comprising a skeleton frame having one rear end and two side portions terminating in free ends, each 40 side portion being bent reversely intermediate the rear end and the free end to direct the free ends of the side portions rearwardly, of a support for each side portion having, a front end to which the side portion adjacent the bend therein is pivotally connected, and, a rear end pivoted on a stationary axis, whereby the skeleton frame as a unit may pivot on the pair of supports, and the skeleton frame and the supports may pivot on the 45 stationary axis. 50

15. In a marking machine, the combination with a guard plate and an ink pad carried thereby, of a skeleton frame having a rear end and two side portions forming a blind opening, each side portion being provided with a groove to 55 receive the opposite side edges, respectively, of the guard plate for sliding movement into and out of the opening.
